UNITED STATES PATENT OFFICE.

DAVID DUMPROPE, OF PEARSON, WISCONSIN.

RAIL-TIE.

1,249,925.

Specification of Letters Patent. Patented Dec. 11, 1917.

Application filed April 14, 1917. Serial No. 161,990.

To all whom it may concern:

Be it known that I, DAVID DUMPROPE, a citizen of the United States, and resident of Pearson, in the county of Langlade and State of Wisconsin, have invented new and useful Improvements in Rail-Ties, of which the following is a specification.

This invention relates to improvements in rail ties.

- 10 The primary object of this invention is to provide a device of the above mentioned character which will effectually prevent the spreading of the rails associated with the same.
- 15 A further object of this invention is to provide means associated with a rail tie which will tend to keep the rail tie in position upon a road bed without other means of securing it thereto.
- 20 A still further object of this invention is to provide a device of the type specified which is strong and durable, simple in construction and easy and inexpensive to manufacture.
- 25 Other objects and advantages will be apparent from the following description taken in connection with the accompanying drawings, and the particular features of novelty will be pointed out in the appended claims.
- 30 Referring to the drawings in which similar characters of reference denote similar parts in the several views:—

Figure 1 is a side elevation of the device, Fig. 2 is a top plan view of the same,

- 35 Fig. 3 is an end view of the device, Fig. 4 is an enlarged view of one of the prongs associated with the device, a portion of a tie being shown in section, and

- 40 Fig. 5 is an enlarged view of one of the prongs.

Referring more particularly to the drawings, the numeral 1 denotes a rail tie which is provided with taper ways 2 and 3 adapted to receive rails 4 and 5 respectively. Each 45 end of the tie 1 is provided with a slot as shown at 6 and 7. Each of these slots 6 and 7 is adapted to receive a bolt as shown by numerals 9 and 10 which serve to hold plates 11 and 12 for securing a rail in position in 50 taper ways 2 and 3. On the opposite side of the taper ways and extending through the tie are bolts 13 and 14 which hold plates 15 and 16 for an obvious purpose.

The portion of the rail tie 1 between the 55 taper ways 2 and 3 is provided with a plu-

rality of openings which extend vertically therethrough, an example of which is shown at 17 in Fig. 4. These openings are arranged preferably as shown near the edges of the tie 1 and are substantially parallel to each other, but it is obvious that they could be placed at suitable places in the tie. Each of these openings is adapted to receive a screw threaded bolt 18, which carries at its end an enlarged portion or prong 19 which is angularly disposed to the bolt 18. Each of the bolts 18, with its associated prong 19, is securely held in position with relation to the tie by a nut 20. As shown clearly in Fig. 2, eight of these prong carrying bolts 70 are used, but it is understood that a greater or less number could be applied.

As shown in Fig. 1 certain of the prongs 19 are disposed in a position opposite to the direction of the remaining prongs. To be 75 more specific, the prongs near the rail 4 are disposed toward said rail, while the prongs near rail 5 are disposed toward rail 5.

With the device as illustrated clearly in Figs. 1 and 2, positioned upon a road bed, 80 it can be readily seen that because of the angular position of the prongs that any spreading of either rail would be counteracted by the position of the prongs in the road bed, that is, should rail 5 tend to 85 spread, the prongs which are angularly disposed toward rail 5 would be forced into the road bed more securely and hence prevent the rail from spreading.

It is also obvious from this construction 90 that the rail tie 1 will be securely positioned upon the road bed.

Having thus described my invention, what I claim as new and desire to secure by Letters Patent is:—

1. A rail tie provided with a plurality of vertically arranged openings, bolts adapted to be secured within said openings, each of said bolts being provided with an enlarged portion angularly disposed with relation to 100 the bolts and adapted to engage in a road bed.

2. A rail tie provided with a plurality of parallel arranged openings, bolts adapted to be secured within said openings, said bolts 105 being provided with enlarged portions angularly disposed with relation to the bolts and adapted to engage in a road bed.

DAVID DUMPROPE.
